United States Patent Office

Des. 189,358
Patented Nov. 29, 1960

189,358

BASEBALL THROWING MACHINE

Paul S. Giovagnoli, 4200 Birmingham Road,
Kansas City, Mo.

Filed July 26, 1960, Ser. No. 61,523

Term of patent 14 years

(Cl. D34—5)

Fig. 1 is a front perspective view of a baseball throwing machine, showing my new design;

Fig. 2 is a top view thereof;

Fig. 3 is an elevational view of one side thereof; and

Fig. 4 is an elevational view of the other side of the baseball throwing machine.

I claim:

The ornamental design for a baseball throwing machine, as shown.
